UNITED STATES PATENT OFFICE.

RICHARD MEGSON, OF LAWRENCE, MASSACHUSETTS.

DESIGN FOR A CAKE.

SPECIFICATION forming part of Design No. 20,434, dated December 23, 1890.

Application filed November 1, 1890. Serial No. 370,082. Term of patent 3½ years.

To all whom it may concern:

Be it known that I, RICHARD MEGSON, a citizen of the United States, residing at Lawrence, in the county of Essex and State of Massachusetts, have invented and produced a new and original Design for Cakes, of which the following is a specification, reference being had to the accompanying drawings, forming part thereof.

10 Figure 1 represents a top view of a cake, showing my design. Fig. 2 is a side view of the same.

The leading feature of my design consists in a star-shaped cake having a scalloped edge 15 and of two colors arranged alternately, with a drop of confection of different colors upon the center of each section.

A B represent the sections of different colors—say A white and B chocolate—arranged alternately, the outer edges of the sections 20 forming scallops C C, substantially as represented. Upon the top of each of these sections A B is a drop of confection, which may be of any suitable color to contrast with the color of the section of the cake upon which 25 it is placed. For instance, the drops of confection D may be white and the drop E red.

What I claim is—

The design for a cake herein shown and described.

RICHARD MEGSON.
